(57) **CLAIM**

The ornamental design for advertising device, as shown and described.

DESCRIPTION

FIG. 1 is a front view of an advertising device;

FIG. 2 is a back view thereof;

FIG. 3 is a left side view thereof;

FIG. 4 is a right side view thereof;

FIG. 5 is a top plan view thereof;

FIG. 6 is a bottom view thereof;

FIG. 7 is a perspective view thereof;

FIG. 8 is another perspective view thereof;

FIG. 9 is a top perspective view thereof; and,

FIG. 10 is a bottom perspective view thereof.

The oblique shade lines represent a transparent surface.

The broken lines showing of the advertising device is for the purpose of illustrating portions of the article and form no part of the claimed design.

1 Claim, 8 Drawing Sheets
